(57) **CLAIM**

The ornamental design for a homogenizer rack, as shown and described.

DESCRIPTION

FIG. 1 is a top perspective view of a homogenizer rack including a plurality of homogenizer devices therein, showing our new design.

FIG. 2 is a bottom perspective view thereof.

FIG. 3 is a right side elevational view thereof.

FIG. 4 is a front elevational view thereof.

FIG. 5 is a left side elevational view thereof.

FIG. 6 is a top plan view thereof; and,

FIG. 7 is a bottom plan view thereof.

The broken lines in the figures represent portions of the article which form no part of the claimed design.
